Attorney.

UNITED STATES PATENT OFFICE.

GUSTAVE C. EGGE, OF NORTII ATTLEBOROUGH, MASSACHUSETTS, ASSIGNOR
TO GEORGE K. WEBSTER, OF SAME PLACE.

DESIGN FOR A BACK FOR BRUSHES OR SIMILAR ARTICLES.

SPECIFICATION forming part of Design No. 28,632, dated May 17, 1898.

Application filed March 11, 1898. Serial No. 673,540. Term of patent 7 years.

To all whom it may concern:

Be it known that I, GUSTAVE C. EGGE, a citizen of the United States, residing in North Attleborough, in the county of Bristol and State of Massachusetts, have invented a new and original Design for the Backs of Brushes or Similar Articles, of which the following is a specification, reference being had to the accompanying drawing, which forms a part 10 of the same.

The figure is a plan view of the back of a brush or hand-mirror containing my design.

A is the back and B the handle of the article ornamented. This style of ornament 15 might be styled "rococo," its characteristic feature being grouping of ornamental scrolls, with realistic flowers and leaves inclosing an escutcheon, on both the head and handle of the article.

20 The ornamentation of the handle B begins with a rose and leaves 1, from the sides of which extend on either side of the handle the shell patterns 2 2, closely fitting between two long scrolls, which ornamentation incloses 25 the escutcheon 4, above which is a foliated

scroll 5. Directly above is a five-petal flower 6, surrounded by leaves covering the lower end of the foliated scroll 7. Above the latter are foliations grouped with flowers 8. At the junction of the head and handle is a flower 9 30 and leaves surmounted by scrolls 10 10. The foliated scrolls 11 11 have two branches, one of which, 12 12, curves toward the center and outlines the escutcheon 13. Above these are the single flowers 14 14, surmounted by the 35 foliated scrolls 15 15. At the top of the escutcheon is a large five-petal flower 16, with surrounding leaves.

What I claim as new, and desire to secure by Letters Patent, is—

40 The design for the back of a brush, or similar article, substantially as herein shown and described.

In testimony whereof I have hereunto set my hand.

GUSTAVE C. EGGE.
